UNITED STATES PATENT OFFICE

156,072

DESIGN FOR A LAPEL BUTTON OR THE LIKE

Donald Campbell, Medford, Oreg.

Application October 15, 1948, Serial No. 149,121

Term of patent 14 years

(Cl. D29—11)

To all whom it may concern:

Be it known that I, Donald Campbell, a citizen of the United States of America, residing at Medford, in the county of Jackson and State of Oregon, have invented a new, original, and ornamental Design for a Lapel Button or the like, of which the following is a specification, reference being had to the accompanying drawing, forming a part thereof.

In the drawing:

Figure 1 is a front elevational view of a lapel button or the like, showing my new design;

Figure 2 is a plan view of the same;

Figure 3 is a sectional view taken on the line 3—3 of Figure 1.

I claim:

The ornamental design for a lapel button or the like, as shown.

DONALD CAMPBELL.
